REFILLABLE BLADE FUSE

Daniel E. Carney, Pittsburgh, Pa., assignor of one-third to James M. Magee, one-third to Harry I. Neaman, and one-third to Marion Herrick Carney, all of Pittsburgh, Pa.

Application September 21, 1932, Serial No. 634,244

8 Claims. (Cl. 200—131)

This invention relates to electric fuses of the enclosed refillable type, and has particular reference to that class of cartridge fuses known in the art as the cartridge blade fuse.

- 5 All such fuses have certain characteristics in common in that they include an insulating casing containing a fuse strip assembly made up of a fusible means connecting spaced blade terminals which project beyond opposite ends of the casing.
- 10 At the casing ends means are provided for holding the fuse strip assembly in fixed position relative to the casing, and for closing the casing ends, generally slotted washers, sectional discs, and like elements, which are separately assembled and 15 retained in place by the clamping action of subsequently applied end caps.

It is a requirement of such fuses that the terminal blades be restrained against rotation with respect to the fuse casing and at the same time 20 that they be restrained against axial movement longitudinally of the casing in either direction.

An object of the present invention is the provision of a fuse casing end cap having self-contained means for holding the terminal blade 25 of a fuse, with which the cap is associated, against rotation with respect to the fuse casing and also for locking the fuse terminal against axial movement longitudinally of the casing.

Another object is the provision in a fuse of an 30 end cap for a fuse casing, combining in a unitary structure, means for closing the end of a fuse casing, means for locking a fuse terminal blade against rotary or longitudinal movement with respect to the casing, and means for attaching 35 the unit to a casing end.

This application is a continuation as to all 40 common subject matter of my prior applications, Serial Number 470,167, on a Refillable blade fuse, filed July 23, 1930, and Serial Number 365,929, for Fuses, filed May 25, 1929.

Other objects, in addition to such as will be apparent to those skilled in the art, include: the provision in a fuse of this character, of a detachable end cap having self-contained means 45 automatically operable by manipulation of the cap for releasably locking a fuse terminal blade against movement relative to the fuse casing; the provision in such a fuse, of means rotatably associated with a portion of the assembled fuse casing structure, and arranged for cooperative locking engagement with a portion of the fuse strip assembly, to restrain the fuse strip assembly against movement axially of the assembled casing; the provision in such a fuse, of an end 55 cap applicable longitudinally of the fuse casing

and having self-contained terminal blade interlocking means for preventing relative movement between the blade and cap axially of the cap; and the provision of an end cap for fuse casings, having casing closure and terminal holding means forming a permanent part thereof. 5

This specification and accompanying drawings are illustrative of certain physical embodiments of the principles underlying the invention, and constitute the best means I have thus far devised 10 for reducing the invention to practice.

Figure 1 is a perspective of a fuse constructed in accordance with the principles of this invention.

Figure 2 is substantially a longitudinal section 15 through the fuse at a right angle to Figure 1.

Figure 3 is substantially a longitudinal section through the fuse at a right angle to Figure 2.

Figure 4 is an end elevation of the fuse with the cap disposed in unlocked position and having 20 the cover washer of the cap removed.

Figure 5 is a view similar to Figure 4 and illustrating the cap in locked position.

Figure 6 is a section on the line 6—6 of Figure 4.

Figure 7 is a group perspective of the elements 25 making up the blade locking end cap.

Figure 8 is a section on the line 8—8 of Figure 2.

Figure 9 is a section on the line 9—9 of Figure 2.

Figure 10 is a perspective of the top terminal blade employed in the fuse assembly.

Figure 11 is a perspective of the casing forming 30 one part of the two-part fuse.

Figure 12 is a perspective of the fuse strip assembly forming the other part of the two-part 35 fuse.

Figure 13 is an elevation illustrating the employment of the casing as a work support in refilling a blown fuse.

In detail, the disclosed embodiment of fuse 40 comprises a casing consisting of a tubular shell 11 of insulating material over each end of which is threaded a metal ferrule head 12 provided with an outwardly extending reduced externally threaded portion 13 having an internal diameter identical with that of the shell. The heads 12 45 are permanently fixed to the shell by suitable retaining elements 14.

As shown in Figure 8, each external end of the heads 12 is formed with diametrically opposed integral webs 15 having opposed edge opening 50 notches 16. The heads are so fixed to the shell that the webs 15 and notches 16 will be in fixed longitudinal alignment at each end of the casing.

The casing is designed to receive a fuse strip 55 assembly comprising two terminal blades 17 and

18 adapted to project beyond the casing ends and having reduced portions 19 and 20 connected by fusible link means here shown as a plurality of bowed fuse links 21 having sufficient inherent stiffness to maintain the terminal blades in properly spaced and aligned relation in handling, thus eliminating the need of an insulating bridge. The shank 19 of blade 17 carries a substantially rectangular flash bar 22 centrally slotted 10 to embrace the shank and abutting the inner edge of the larger contact portion, being rigidly secured to the shank by solder and by striking over the metal thereof. This bar is narrow, having a width not much greater than the thickness of its 15 associated blade and at each end the bar extends slightly beyond the edges of the blade, being curved in conformity to the casing head wall.

As best shown in Figure 10, the terminal blade 17 has its edges recessed to provide shoulders 23 20 in advance of the flash bar. These shoulders each form the rear wall of the formative recess, the forward wall 24 of each recess being inclined outwardly from the recess bottom to the edge of the blade.

25 The blade 18 is formed with a permanently secured closure cap 33 for the casing end, consisting of a circular plate 28 embracing the blade and carrying on its inner face a guide plate 29 shaped to seat in and conform to an end of the casing 30 with inturned guide fingers 30 seating in the casing head notches 16. Plates 28 and 29 are rigidly connected as a unit by screws or rivets 31 and the unit thus formed is fastened on the blade between the flash bar 25 and a cotter pin 32.

35 Forming a part of the cap 33 and rotatably associated with the closure plate 28 is a rotatable sleeve portion 33' threaded for engagement over the casing head 13 and formed with an integral annular flange 34 internally thereof intermediate 40 the sleeve ends. A covering washer 35 slotted to receive the terminal blade, seats over the outer face of the flange 34 within the confines of the cap and this washer is coupled to the closure plate 28 by rivets or screw bolts 36, the shanks of which, 45 between the washer and plate, are surrounded by spacer sleeves 37 which maintain a freely rotatable relationship between the washer and plate and the cap flange 34 confined therebetween.

At its opposite end, generally referred to in service as the top, the casing carries an end cap 38 50 provided with an internally threaded sleeve portion 38' for detachable threaded engagement over the head 13 and having an intermediate, internal, integral annular flange 39 of an internal diameter less than that of the casing. In cross-section 55 the flange is shaped to engage in and conform to the recesses 23-24 of the terminal blade 17, which, in a certain position of the cap, may be moved axially of the casing through substantially 60 U-shaped diametrically opposed recesses 40 in the flange, the depth of the recesses being such that when aligned with the blade the same may be passed freely therethrough.

Rotatably coupled to and forming a permanent 65 part of the end cap 38 is a casing end closure plate 41, which when the cap is threaded home, seats over the head 13 and closes the end of the casing. Plate 41 is in the form of a flat disc provided with a central slot 42 to receive the terminal blade. Rigidly attached to the inner face of the closure plate, as by rivets 43, so as to form 70 a unit therewith, is a guide member 44 comprising a plate shaped to conform to and seat in the end of the adjacent casing head 13 between the webs 15. This plate 44 is provided with inward-

ly directed guide fingers 45 having rounded tips, which pass through and seat in the notches 16 of the webs 15 when the cap is applied. Plate 44 is also slotted to engage over the terminal blade. 5

The elements of cap 38 are permanently coupled in freely rotatable relation with respect to each other by means of an outer covering washer 46 centrally slotted to receive the terminal blade and which seats loosely against the outer face 10 of the cap flange 39 being connected to the plates 41 and 44 by rivets or screw bolts 47. Spacer sleeves 48 surround the screw bolt shanks between the cover washer and end closure plate to insure against any binding of these elements 15 against the cap flange which is confined therebetween. Markers 49 are provided on the outer rim of the cap 38 in diametrical alignment with the flange recesses 40.

In assembling the fuse the unitary and cap 20 38 comprising the sleeve 38', plate 41 and covering washer 46, is threaded over an end of the casing head 13, such as the left hand end as seen in Figures 1, 2 and 3. The cap is screwed home to its limit and is then given a reverse turn sufficient 25 to align the markers 49 and the blade slot in the cover washer 46. As washer 46 is fixed with respect to the end closure plate 41 by virtue of the screw bolts 47 the washer and plate will remain stationary, being held against rotation by the engagement of plate 44 and guide fingers 45 between the casing head webs 15 and notches 16 through which the guide fingers pass in advance of the threading of the cap. The cap sleeve 38' and its integral locking flange 39 alone 30 rotates. When the markers 49 align with the blade slot the lock flange recesses 40 will be similarly aligned.

The fuse strip assembly comprising the blade 18 with its permanently connected end cap unit 40 33, fuse links 21 and terminal blade 17 is then inserted through the open end of the casing from right to left, the blade 17 passing through the aligned openings of the end cap unit 38 until the flash bar 22 of the blade engages against cap 45 plate 44 at which point the recesses in blade 17 will occupy the plane of the locking flange 39 and the guide fingers 30 of end cap unit 33 will have engaged the recesses 16 in the webs 15 of the adjacent casing head sufficiently in advance 50 of threading engagement of the cap 33 to anchor the terminal blade 18 against rotation in the casing while the cap is screwed home. The advancing movement of cap 33 causes its flange 34 to bear against plate 28 and clamp the same 55 against the casing end.

With the parts thus assembled the end cap 38 is rotated to disalign the markers 49 from blade 17 whereupon the cap flange 39 moves into the blade recesses 23-24 and interlocks with the blade preventing any axial movement of the terminal blade 17 with respect to the cap and casing. Due to the fact that the slotted plates 41, 44, and cover washer 46 embrace the blade it is evident that the blade will be held against rotation 65 as the seating engagement of plate 44 and guide fingers 45 in the adjacent casing head prevents rotary movement of these elements.

When it is desired to unlock the blade 17 the cap sleeve 38' is rotated to align the markers 49 70 with the blade, which will align the notches 40 with the blade permitting it to be moved axially through the cap.

Venting of the fuse is accomplished through a circular vent groove 50 provided in the inner 75

face of the flange 39 in cap 38 and opening to the blade notches 40.

In service the fuse is a two-part assembly, one part A as shown in Figure 11 comprising the 5 casing 11 carrying the cap 38, and the other part B, shown in Figure 12, comprising the fuse strip assembly which is inserted in the casing as described.

Referring to Figures 1 and 13 and assuming 10 the fuse to have been blown, a refilling can be accomplished without the necessity of removing a plurality of elements and allowing them to lie on a work bench or shelf and thus pick up dirt and grease. In making a refill the cap 38 is 15 tractively rotated, its movement causing the lock flange 39 to move out of engagement with the blade 17 and placing the notches 40 in registry with the closure plate slot 42.

The cap 38 is then unscrewed, and by virtue of 20 its permanent, non-slidable connection with the blade 18, said blade and cap are removed as a unit. Holding the casing in a vertical position, as seen in Figure 13, the blade 17 is pushed inwardly and allowed to drop through the casing. 25 Blade 18 is then inserted through cap 38, seating in the slot of its associated structure until cap 38 rests on cap 38 as seen at the upper part of Figure 13.

New fuse links 21 are then connected to the 30 upstanding blade portion 20, after which the terminal 17 is connected with the free ends of the fuse links. This completes the assembly of the fuse strip which is then removed from cap 38 and inserted as an entirety through the open 35 end of the casing, in a manner previously described in detailing the assembling of the two-part fuse thus formed.

In the refilling operation the casing 11 serves 40 as a work holder or supporting vise, and no part of the entire fuse leaves the hands of the person refilling.

An important feature of the invention lies in the provision of a clearance of from one ten thousandth to one fifteen thousandth of an 45 inch between the terminal blade 17 and the slots in cover washer 46 and plates 41 and 44, and between the terminal blade 18 and the slots in cover washer 35 and plates 28 and 29. This clearance permits of a very slight rotational play 50 of the blades relative to the casing and also of a slight axial rocking of the blades, whereby the blades may align themselves on engagement in the usual fuse holder contact clips, not shown. This self-aligning feature of the terminal blades 55 insures full contact and thus avoids overheating.

I claim:

1. In a fuse, a casing, an end cap having rotatably detachable engagement with one end

thereof, a closure member in permanently coupled connection with said cap and shiftable thereon, a terminal blade movable axially through said closure member and cap, and blade locking means carried by said cap and locking said terminal blade against movement axially through said closure member and cap. 5

2. In a fuse, the combination with a casing and a fuse strip assembly having a terminal projecting through an end of the casing, of an end cap engageable with the casing end, and means permanently connected to said cap for locking said terminal against axial and rotary movement with respect to the casing. 10

3. An end cap for fuse casings, including a casing attachable portion, and a fuse terminal interlocking engageable member permanently connected thereto within the confines of the cap. 15

4. An end cap for fuse casings, including a casing engaging portion, an internal annular flange thereon arranged for interlocking engagement with a terminal blade, and means coupled to said flange for engaging a casing end to prevent rotary movement of the terminal blade 20 with respect thereto. 25

5. An end cap for fuse casings, including a casing attachable portion, a fuse terminal engageable interlocking member forming a part of said cap, and a casing end closure member loosely coupled to said interlocking member. 30

6. In a fuse, an end cap comprising a casing engageable sleeve portion, an internal flange on said cap adapted for interlocking engagement with a terminal blade, and a member rotatably coupled to said flange and adapted for fixed engagement with a casing when the cap is applied, said member being arranged to embrace a fuse terminal. 35

7. An end cap for fuse casings, including a casing engaging portion, an internal annular flange thereon arranged for interlocking engagement with a terminal blade, casing end closure means associated with said flange and engageable with a casing end to prevent rotary movement of the terminal blade with respect thereto, and said flange having a vent groove in the inner face thereof. 40

8. An end cap for fuse casings, comprising a casing engaging portion, an internal annular flange integral with said casing engaging portion and disposed between the opposite ends thereof, said flange being arranged for interlocking engagement with a terminal blade, and means coupled to said flange for engaging a casing end to prevent rotary movement of a terminal blade 50 with respect thereto. 55

DANIEL E. CARNEY.
